ATTORNEY

UNITED STATES PATENT OFFICE.

LEONARD L. CONKEY, OF MARNE, MICHIGAN, ASSIGNOR OF ONE-HALF TO WALTER S. DAVIS, OF FLUSHING, MICHIGAN.

POULTRY ROOST.

Application filed June 17, 1922. Serial No. 568,997.

To all whom it may concern:

Be it known that I, LEONARD L. CONKEY, a citizen of the United States, residing at Marne, in the county of Ottawa and State of Michigan, have invented certain new and useful Improvements in Poultry Roosts; and I do hereby declare the following to be a full, clear, and exact description of the invention, such as will enable others skilled in the art to which it appertains to make and use the same.

This invention relates to poultry roosts and the improvement pertains more particularly to that class of poultry roosts in which the wooden perch is automatically kept saturated with disinfectant liquid which is carried by the capillary action of a fabric lining from a suitable reservoir to the wooden perch.

20 My present improvement relates more specifically to the construction of a roost of the class referred to whereby the objects of my improvement are attained.

These objects are to provide a simple, yet inexpensive sanitary vermin proof roost in which the edges of the platform or perch project laterally beyond the rim of the trough containing the disinfectant, so that the perch or board will not only form a 30 cover for the trough, but will also protect the edges of the trough from dirt and will protect the poultry's feet from the metal.

I also secure the trough permanently to the perch as distinguished from that class of devices in which the trough, fabric lining and perch are separable for cleaning, because I have found in practice that a perch made according to my present improvement need not be capable of being taken apart for 40 cleaning, since it affords no lodgment for dirt in crevices or in the fabric lining itself.

With these and certain other objects in view, which will appear later in the specification my improvement comprises the devices described and claimed and the equivalents thereof.

In the drawings, Fig. 1 is a perspective view of a frame carrying a number of roosts made in accordance with my improvement. 50 Fig. 2 is a part sectional perspective view of the device.

As is clearly shown in the drawings, my improved roost consists in the board or perch 1 of the usual type, beneath which is

permanently secured a V-shaped trough 2 having laterally projecting flanges 3 and a trough-shaped fabric 4, the outward edges of which form strips 5 secured between the trough flanges 3 and the under side of the perch 1.

The side edges 6 of the perch 1 project outwardly beyond the edges of the flanges 3 and beyond the edges of the fabric strips 5. When the trough is supplied with disinfectant liquid the fabric carries it by capillary attraction upward and outwardly, thoroughly saturating the strips 5 which lie between the flanges 3 and the under side of the board or perch 1, so that each of the strips 5 comprises a long and relatively wide area 70 of absorbent material that soon thoroughly saturates the entire board or perch with the disinfectant liquid. These strips 5, the fabric 4 and the trough 2 remain permanently attached to the perch 1. It is not necessary 75 to take them apart for cleaning or replacement, as the wick is thoroughly protected from dirt, and the outwardly projecting side edges 6 of perch 1 prevent dirt from accumulating on the outside of the trough to any 80 great extent and entirely prevent dirt from getting inside the trough.

Preferably I make the trough somewhat longer than the perch 1 and provide the projecting part of the trough with a slideable 85 cover 7 so that the trough may be filled with disinfectant liquid or emptied or rinsed out when desired.

Having thus described my invention, what I claim and desire to secure by Letters Patent is:

1. In a roost, in combination, a perch, a trough having laterally projecting flanges, said flanges secured to the under side of said perch, a fabric lining suspended in said trough, the lateral edge of said fabric lining received between said perch and flange and extending lengthwise thereof, the side edges of said perch projecting laterally beyond the edges of said flanges, for the purposes 100 set forth.

2. In a roost, in combination, a perch, a trough having laterally projecting flanges, said flanges secured to the under side of said perch, a one-piece V-shaped fabric suspended in said trough, the lateral edges of said fabric secured between said perch and said flanges, and extending lengthwise thereof,

the side edges of said perch projecting laterally beyond the edges of said flanges, for the purposes set forth.

3. In a roost, in combination, a perch, a trough having laterally projecting flanges, said flanges secured to the under side of said perch, a fabric lining suspended in said trough, the lateral edge of said fabric lining secured between said perch and flange and 10 extending lengthwise thereof, the side edges of said perch projecting laterally beyond the

edges of said flanges, one end of said trough projecting beyond the end of said perch, and a removable cover on the projecting end of said trough.

15

In testimony whereof, I affix my signature in presence of two witnesses.

LEONARD L. CONKEY.

Witnesses:
